UNITED STATES PATENT OFFICE.

W. H. STROUP, OF PHILADELPHIA, PENNSYLVANIA.

IMPROVEMENT IN SLEIGH-RUNNERS.

Specification forming part of Letters Patent No. **69,508**, dated October 1, 1867.

To all whom it may concern:

Be it known that I, W. H. STROUP, of Philadelphia, in the county of Philadelphia, and in the State of Pennsylvania, have invented certain new and useful Improvements in Sleigh-Runners; and I do hereby declare that the following is a full, clear, and exact description thereof, reference being had to the accompanying drawing, and to the letters of reference marked thereon, making a part of this specification.

My invention consists in so constructing the runner of a sleigh in such a manner as to attach it under and directly to the wheels of light carriages, children's carriages, or other vehicles having either two or four wheels, or under anything that runners are to be placed beneath; also, in firmly securing the wheel of the vehicle when attached thereto; also, in making the runners portable and easy to transport.

In the annexed drawing, A represents the forward portion of the sleigh-runner, which is formed in the usual manner, and usually constructed of wood, metal, or both. To the rear end of this runner is hinged (C) a short section of a runner, A', and by means of its said hinge may be folded up or allowed to remain open to form a longer runner, as desired. Upon the top of these sections A A' are placed suitable fastenings, to which the vehicle-wheels are connected.

B represents a metal keeper, which is secured to the upper forward end of the main section A' by means of a bolt, e, having a screw-thread, which passes through the open part of keeper and runner, where it is stationed by the nut x. This keeper can be readily extracted from the runner whenever required.

In attaching the vehicle to the runner the keeper is taken off and clamped around the wheel and then reattached to the runner. When the runner is required for a two-wheeled vehicle the rear section, A', can be detached entirely by means of the hinge C or folded up out of the way. The wheels are secured to the runner by the fastening on the top of the section and the keeper at the end of section A.

Having thus fully described my invention, what I claim as new, and desire to secure by Letters Patent, is—

The runners A A', hinge C, and keeper B, arranged in the manner and for the purposes specified.

In testimony that I claim the foregoing I have hereunto set my hand this 6th day of August, 1867.

W. H. STROUP.
